UNITED STATES PATENT OFFICE.

MAURICE B. FREDERICKS, OF WALTHAM, MASSACHUSETTS, ASSIGNOR TO THE FIBER-BONE COMPANY, OF WALTHAM, MASSACHUSETTS, A CORPORATION OF MASSACHUSETTS.

DESIGN FOR A PICKER FOR A LOOM.

59,003.

Specification for Design. Patented Sept. 13, 1921.

Application filed April 13, 1921. Serial No. 461,102. Term of patent $3\frac{1}{2}$ years.

To all whom it may concern:

Be it known that I, MAURICE B. FREDERICKS, a citizen of the United States, residing at the city of Waltham, county of Middlesex, and State of Massachusetts, have invented a new, original, and ornamental Design for Pickers for Looms, of which the following is a specification, reference being had to the accompanying drawing, forming part thereof, in which—

Figure 1 is a perspective view of a picker for a loom, showing my new design, and Fig. 2 is an end elevation of the same.

I claim:—

The ornamental design for a picker for a loom, as shown.

MAURICE B. FREDERICKS.
